UNITED STATES PATENT OFFICE.

AUGUST KOENIG, OF MURPHYSBORO, ILLINOIS, ASSIGNOR OF ONE-HALF TO WILLIAM KOENIG, OF MURPHYSBORO, ILLINOIS.

MAIL BOX.

Application filed April 10, 1922. Serial No. 551,200.

To all whom it may concern:

Be it known that I, AUGUST KOENIG, a citizen of the United States, residing at Murphysboro, in the county of Jackson and 5 the State of Illinois, have invented certain new and useful Improvements in Mail Boxes, of which the following is a specification.

This invention relates to that type of mail 10 box used generally on rural routes, mail being both collected and deposited by the carrier, and also by the owner of the box.

The object of the invention is a box which 15 can be conveniently used by the carrier without his dismounting from his vehicle.

The invention consists in the novel features of construction and combination of parts hereinafter described, pointed out in the claims and shown in the accompanying 20 drawings, in which:—

Figure 1 is a vertical longitudinal section, the box being closed.

Figure 2 is a similar section, the box being open.

Figure 3 is an end elevation.

Figure 4 is a vertical, transverse section.

In the drawing 1 designates the box having a cover 2, these being of the usual size and shape. The front end of the cover portion, as shown at 3, is inwardly offset with 30 respect to the front end 4 of the body portion of the box.

The space between these end portions 35 forms a letter drop, said space being normally closed by a hinged lid 5 which works in said drop opening and in closed position is in contact with both the end members 3 and 4, as shown in Figure 1. This lid is also shown in closed position in Figure 3. 40 To open it the lower end is lifted up and the lid swings back into the box leaving a space below it through which letters can be dropped.

Within the box and to each side are slidably secured segmental links 6 longitudinally slotted as at 7, the links slide on pins 8 carried by the box sides. Curved links 9 are pivotally connected at 10 to the free ends of the links 6, and to the free ends 50 of the links 9 are connected rods 11 which in turn are slidably connected to vertically arranged brackets 12 carried by the inner side of the front wall 4.

A drawer 13 is slidably placed in the bottom of the box 1 and the pivot pins 10 connecting the links 6 and 9 are secured to the sides of said drawer or tray. In other words the pins 8 on which the links 6 slide and which are guide pins are fixed to the box, while the pins 10 which are pivotal points for both sets of links are fixed to the drawer. A finger grip 14 is carried by the front end of the drawer and projects outwardly beyond the bottom of the box 1. Adjacent the front end of the drawer is 60 placed a spring metal plate 15, fixed to the front of the drawer at one end, but slightly spaced from it, and pressed at the other end toward the end of the drawer by a spring 15^a. The plate 15 co-operating with the front end member of the drawer forms a letter clip or holder, within easy reach of the carrier.

The usual signal indicator 16 is carried by one side of the box. Under normal conditions the parts assume the position shown in Figure 1, but as the drawer is pulled outwardly the links 6 and 9 and the rods 11, sliding on the brackets 12, lift the hinged front end 4, as shown in Figure 2.

What I claim is:

1. In a mail box, a body portion, a drawer, a hinged front member, pins carried by the sides of the drawer, links connected to said pins and turning thereon, means connecting a portion of said links to the hinged front member, and guides carried by the box and guiding sliding movement of the other links, as and for the purpose set forth.

2. In a mail box, a front member hinged at the top, a slideable drawer having a pull handle projecting beneath said hinged end, guide pins carried within the box and to opposite sides of same, curved slotted links working on said pins, a set of oppositely arranged links arranged within and at the sides of the drawer, common pivot pins for both sets of links, vertical brackets carried by the inner face of the front end member, and rods connected at one end to the second set of links and slidably connected at their opposite ends to said brackets, respectively.

In testimony whereof I affix my signature.

AUGUST KOENIG.
